UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 27,003, dated April 27, 1897.

Application filed March 23, 1897. Serial No. 628,918. Term of patent 7 years.

To all whom it may concern:

Be it known that I, ADOLPH PETZOLD, a citizen of the United States, residing in the city of Philadelphia, Pennsylvania, have invented and produced a certain new and original Design for Rugs, of which the following is a full, clear, and exact description, reference being had to the accompanying drawing, forming a part of this specification.

10 My invention relates to the surface ornamentation of a woven rug; and it consists of the design therefor shown in the aforesaid drawing, the distinguishing features of the design being a narrow rectangular border A 15 of straight parallel lines and between them

an irregular vine-like figure A'. Within the border is a figure having a rectangular outline B, with top and bottom cross-bars C and a central irregular-shaped figure D, with varied ornamentation filling up the field center. ²⁰

I claim as new and of my invention—
The design for a rug, substantially as set forth.

In testimony whereof I have hereunto affixed my signature this 26th day of February, ²⁵ A. D. 1897.

ADOLPH PETZOLD.
